UNITED STATES PATENT OFFICE.

SAMUEL D. BUTTERWORTH, OF LANSING, MICHIGAN.

METHOD AND APPARATUS FOR LOADING AUTOMOBILES.

1,304,656.

Specification of Letters Patent. Patented May 27, 1919.

Application filed January 15, 1918. Serial No. 211,927.

To all whom it may concern:

Be it known that I, SAMUEL D. BUTTERWORTH, a citizen of the United States, residing at Lansing, in the county of Ingham and State of Michigan, have invented a new and useful Improvement in Methods and Apparatus for Loading Automobiles, of which the following is a specification.

This invention relates to a method of loading automobiles and also the apparatus. It is the desire during the present shortage of freight cars to use flat cars for loading and carrying automobiles, but the ordinary flat car will only carry two automobiles when loaded in the customary way. This is obviously a rather expensive way of shipping. It is the object of the present invention to make flat cars available for carrying a maximum number of automobiles.

20 In the drawings,—

Figure 1 is an elevation of a flat car showing an automobile being driven into its final position.

Fig. 2 shows a flat car completely loaded.

25 Fig. 3 is an enlarged detail view of the framework and the automobile in final position.

Fig. 4 is an end elevation of the framework.

30 Fig. 5 is a detail showing the oblique braces for the frame-work.

Fig. 6 is a detail including the section of a wheel showing how the wheel is strapped down.

35 Fig. 7 is a section of the stirrup that holds the front wheels.

Fig. 8 is a plan view of the same.

Fig. 9 is a side elevation partly in section of one of the skids up which the front wheels 40 are driven.

Fig. 10 is a perspective of the approach to the skid.

The outline of a flat car is apparent in Figs. 1 and 2. Mounted upon its platform is a rectangular frame-work comprising 45 really two frames of angle irons at each side of the car. Each frame is braced longitudinally by the diagonals *a* and transversely by the diagonals *b*. Note in Fig. 5 that these diagonals *b* are provided with two bolt holes

so that the upper one can be used when the diagonal is attached directly to the platform of the car and the lower one can be used where a small plank *c* is interposed between the foot of the diagonal and the platform 55 so as to give a footing to the diagonal, which might not otherwise be possible by reason of the damaged edge of the flat car platform. In Fig. 4 is shown a pair of diagonals which can be used at the ends of the frames for 60 connecting the two frames together in the form of a bracing X. These are usually not put in place until the car is loaded, as it may be necessary to drive the automobiles the length of several cars before they reach the 65 loading place.

A stirrup for the front wheels of the automobile is formed by the device shown in Figs. 7 and 8, comprising a pair of angle bars *e*, *e*, which bridge the tops of the frames 70 and also thereby serve to tie the frames together, and which are bolted to the top angle bars of each frame. Note that the top longitudinal angle bars of each frame are provided with a plurality of bolt holes *f*. This 75 enables the crossing angle bars to be bolted at different positions along the frame-work to accommodate the frame-work to cars of different wheel bases.

Referring to Figs. 7 and 8, it will be seen 80 that as well as the angle bars *e*, there are riveted to each angle bar *e* two other angle plates *g*, each consisting of a web and two flanges integral therewith at an obtuse angle. At the ends of these plates and to the top 85 flanges are bolted the strips *h*, which at the end toward which the automobile approaches, continue down to form a rest *i* to receive the end of the skid *j* (Fig. 1). The skid is detailed in Fig. 9 and also shown in Fig. 4. 90 Referring to Fig. 9, the skid is made up in the main by a trough-like member which at its upper end is provided with a pair of holes *k*, through which may be dropped pins which also drop through the holes *m* (Fig. 95 8) of the rests that temporarily hold the top of the skid to the stirrup. The base of the trough-like member is supported on a pair of legs *l* and also on an oblique brace *n*. The legs protrude slightly forward of the skid 100

to form a seat *o* upon which may be rested the upper end of the approach skid *p*.

This skid and approach construction is important, for it enables loading in a way that 5 would not otherwise be possible. Referring to Fig. 1, it will be seen that the car is driven up first the approach *p* and then the front wheels strike the skid *j*. The car can now be stopped and the approach *p* taken out, the 10 power again applied to the automobile, and the same driven up until the front wheels drop into the stirrups. In short, the approach *p* serves only to lift the front wheels on to the skid. After the approach is taken 15 away, the front wheels continue the rest of the way up while the rear wheels are driven along on a level. After the front wheels are in the stirrups, the skids themselves may be removed and used in the same manner to lift 20 the second car into the next succeeding pair of stirrups.

The front wheels may now be locked securely in the stirrups by means of the clamping strips *g*, which are bolted through slots 25 to the strips *h* and provided with a raised portion to bridge the wheel felly between the spokes. The slotted construction enables the clamping strip to be applied to the 30 wheels regardless of just where they happen to drop into the stirrup.

The rear wheels are chocked both front and back by the inverted V's and the block *t* respectively. The canvas is passed between the spokes and over the felly and nailed 35 on by the cleats *u* (Fig. 6).

The car is, therefore, firmly held both at the front and rear and the cars themselves become part of the bracing of the frame-work. It is very evident that by reason of 40 their oblique disposition, not only does each occupy less horizontal space but they are caused to overlap in about half the horizontal space that each one occupies. Hence the number that can be gotten into a given 45 length of platform is very much increased. It is also to be borne in mind that no tackle or other lifting devices are necessary to place the cars. They are driven into their place by their own power. The unloading operation 50 is simply a reversal of the operations already described.

What I claim is:

1. The method of loading automobiles on a frame-work and platform, which consists 55 in driving the front wheels up an inclined skid and approach to the skid, removing the approach, continuing the driving of the car to its final position, and securing the front wheels to the frame-work.

60 2. The method of loading automobiles upon a frame-work and platform, which consists in driving the front wheels over a skid and approach, removing the approach, continuing the driving until the front wheels

rest at the top of the frame-work and the car 65 is in oblique position, and the repeating of the operation with the second car and bringing the second car in overlapped relation with respect to the first car.

3. A frame-work for loading automobiles, 70 comprising a pair of frames, pairs of cross bars connecting the tops of the frames, and stirrups located at the ends of the cross bars for supporting the front wheels of the automobiles and supporting the automobiles in 75 inclined and overlapped relation.

4. A frame-work for loading automobiles, comprising a pair of frames between which automobiles may be driven, cross bars connecting the tops of the frames, stirrups supported at the top of the frame and comprising each a pair of side strips, and a clamping strip to engage over the front wheel to 80 secure the same in place and support the automobiles in inclined and overlapped relation. 85

5. The method of loading automobiles upon a frame-work and platform, which consists in driving the front wheels over a skid and approach, removing the approach, 90 continuing the driving of the car over the skid to its final position, removing the skid, and the repeating of the operation for the second car to bring the second car in overlapped relation with respect to the first car. 95

6. The combination of a frame-work for loading automobiles, comprising a pair of frames between which the automobiles may be driven, stirrups at the top of the frame for supporting a pair of automobile wheels, 100 and removable skids by which one set of wheels may be forced up into the stirrups and the skids removed.

7. The combination of a frame-work for loading automobiles, having a pair of 105 frames between which the automobiles may be driven, and pairs of stirrups located at the top of the frame to hold each a pair of automobile wheels, skids and removable approaches, the said approaches being removable when the forward set of wheels is driven up part way to the top of the skids, after 110 which the forward set of wheels may be driven the rest of the way up the skid.

8. A frame-work for loading automobiles, 115 comprising a pair of frames between which automobiles may be driven, stirrups comprising side strips having continuations forming rests for the top end of the skid, and clamping means between the side strips for 120 engaging the front wheels of an automobile which is driven up the skid into the stirrup and holding the automobiles in inclined and overlapped relation.

9. In a frame-work for loading automobiles, a pair of frames between which automobiles may be driven, and a plurality of stirrups supported at variable positions 125

along the two frames to support the automobiles in diagonal and overlapped relation and be adjustable to accord with varying wheel bases of the automobiles.

5 10. In a frame-work for loading automobiles on flat cars, one or more upright members on the frame-work, and transverse diagonal braces having each a pair of holes by

which the braces may be bolted to the upright and through one or the other of the 10 holes depending upon the necessity of interposing a plank under the foot of the brace.

In witness whereof I have hereunto set my hand on the 4th day of January, 1918.

SAMUEL D. BUTTERWORTH.
